MACHINE FOR DRILLING AND/OR FILLING
BRUSH STOCKS

Russell Henry Richard Parker, Portchester, England, assignor to J. Evans & Son (Portsmouth) Limited, Portsmouth, England, a British company

Filed Jan. 13, 1964, Ser. No. 337,306

Claims priority, application Great Britain, Jan. 28, 1963, 3,508/63

6 Claims. (Cl. 300—3)

This invention relates to apparatus for drilling and/or filling brush stocks.

To enable the desired pattern of holes to be drilled and filled in a brush stock, it is the usual practice to support the brush stock on a pivotally mounted workholder which is given a predetermined angular movement to position the brush stock in the desired series of angularly related positions relative to the drilling and filling devices of a brush making machine.

With the increasing complexity of brush types and filling arrangements now required, conditions sometimes arise when the angular movements required to be imparted to the brush stocks are beyond the practical capacity of the standard workholder arrangements.

According to the present invention, apparatus for drilling or filling brush stocks comprises one or more workholders for supporting brush stocks to be drilled or filled and one or more tools for effecting the drilling or filling operation, the tool or tools being mounted for pivotal movement relative to the workholder or workholders to enable the desired angular relation between the workholder or workholders and tool or tools to be produced for effecting end spread drilling or filling.

The workholder or workholders is or are pivotally mounted, and accordingly by pivoting the drilling and filling tools, it is possible to reduce the pivotal movement that would normally be imparted to the workholder, for example, when drilling holes or inserting tufts at extreme angular positions in the brush stock. Further, a combined relative pivoting movement will be possible which will, in certain cases, enable the said angle to be increased beyond what would normally be possible by pivoting only the workholder.

To enable the invention to be fully understood, it will now be described, by way of example, with reference to the accompanying drawings in which:

FIGURE 1 is a side view of apparatus according to one embodiment of the invention;

FIGURE 2 is an end view thereof; and

FIGURE 3 is a plan view; and

FIGURE 4 is a section on line A—A of FIGURE 1 on an enlarged scale.

As shown in the accompanying drawings, the apparatus comprises a base 1 supporting vertically extending bearings 2 in which pillars 3 are slidably mounted, the latter supporting the horizontally extending cross beam 4.

A runner 5 is provided at each end of the cross beam and which serves to support a slide 6. Pairs of support plates 7, 8 extend upwardly of the slides 6, the plates having apertures 7a, 8a respectively at vertically spaced intervals, a pivot pin 7b being positioned in two aligned apertures. The plates 7 are connected at their lower ends to the slides 6, and the plates 8 are connected adjacent their upper ends to cross bars 9, 9a which extend between and are attached to opposed side bars 10.

The side bars 10 and cross bars 9, 9a and 11 form a cradle-like support for an assembly of workholders a, a¹, b, b¹, c, the cradle being supported by the plates 8 which are pivotally connected to the plates 7 so that the cradle is capable of pivotal movement, the degree and amount of such movement being varied, if desired, by positioning the pin 7b in different pairs of aligned apertures 7a, 8a.

2

As shown more particularly in FIGURE 4, each workholder comprises a base 12 and opposed side plates 13, 14. A pair of clamping jaws is provided on the base comprising a fixed jaw 15 and a movable jaw 16, the latter being adapted to be reciprocated relative to the jaw 15 by a piston rod 17 connected with a piston operating in a cylinder 18. Fluid under pressure is normally supplied to the cylinder 18 to move the jaw 16 inwardly into clamping position so that the opposed ends of a brush stock positioned on the base 12 will be clamped between the jaws 15, 16. When, however, the brush stock is to be unloaded and a new one substituted, the supply of fluid under pressure will be reversed to move the jaw 16 outwardly to unclamp the brush stock and then to move it inwardly when a new brush stock is positioned on the base so as to clamp it.

The side plates 13, 14 are respectively pivoted to support plates 19, 20 by pivot pins 20b inserted through pairs of aligned apertures 13a, 19a, 14a, 20a, the plates 13, 14 being also respectively pivoted by pins 21 to arms 22. The arms 22 of the pair of workholders a, a¹ are directly secured to side bars 23 extending in spaced parallel relation to the side bars 10. The arms 22 of the pair of workholders b, b¹ are connected to a member 22a to which is attached a housing generally indicated by 24 and including a guideway in which the side bars 23 are slideable. A plunger 25 in the housing is normally urged by a spring 26 to engage one of two notches in the member 23a attached to the side bars 23 to enable the workholders b, b¹ to be locked to the said side bars. Only one of these two notches is shown, as 27a in FIG. 1, since the other is hidden by the workholder. The plungers are adapted to be released from locking engagement by supplying fluid under pressure to a cylinder 28 to actuate a piston rod 28a connected with the plunger.

Each support plate 19, 20 is secured to a guide channel 29 which slidably receives the side bars 10.

The guide channel 29 of the pair of workholders b, b¹ are connected to a transverse bar 30 having a depending lug 31 to which a piston rod 32 is attached. This rod is connected with a piston operating in a cylinder 33 which is supported on a transverse strut 34 extending between the side bars 10 so that by supplying fluid under pressure to the cylinder 33, the piston rod 32 will be reciprocated to slide the pair of workholders b, b¹ as a unit relatively to the side bars 10, 23, when the plunger 25 is unlocked.

A plate 35 is supported on transversely extending bars 36 and serves to support a boring tool D, a filling tool F and a control point C.P. the latter being adapted to cooperate in known manner with a "control" plate mounted on the workholder c. The boring tool D is carried by a slide 37 slidably mounted in guideways 38, the slide 37 being connected with a piston rod 39 of a piston mounted in the cylinder 40 such that by supplying fluid under pressure to the cylinder, the boring tool can be moved transversely so as to be positioned alternately over the workholders a, a¹.

The workholders b, b¹ are adapted to be moved transversely so as to be alternately positioned under the filling tool F.

During the drilling and filling of a brush stock, it is necessary, when end and/or side spread drilling and filling is to be effected, for the brush stock and tools to be disposed in predetermined angular relation. For this purpose the workholders are mounted to permit pivotal movement relative to the tools as hereinbefore described.

The present invention also provides for the tools to be pivoted relative to the workholders for effecting end spread drilling and filling effect.

As illustrated in FIGURES 1 to 3, the opposite ends of the tool supporting bars 36 are attached to side plates 41 pivoted at 42 to side frame members 43. One of the

side plates is pivoted at 44 to a link 45 which is pivotally connected to a lever 46 having a follower 47 riding on a cam 48.

The cam 48 is continuously rotated when the machine is in operation and is contoured to impart a predetermined pivotal movement to the lever 46 during a drilling and filling operation, the movement of the lever being transmitted by the link 45 to the tool supporting assembly to impart a predetermined pivotal movement to the tools relative to the workholders.

The pivotal movement of the workholder assembly is controlled by a cam 49 which effects the pivotal movement of a lever 50 having one end pivoted at 51 to the base 1, and the other end pivoted at 52 to a link 53 connected through a lever 54, and a link 55 to a plate 56 secured to the cross member 11 which extends between the side bars 10. The pivotal movement of the lever 50 will accordingly be transmitted to the plate 56 to pivot the workholder assembly about the pivot pins 7b.

It will accordingly be noted that the workholders can be pivoted relative to the tools and that the tools can also be pivoted relative to the workholders.

In order that the workholders may be presented in correct angular relation to the tools when effecting end spread drilling and filling, it will be necessary to effect a predetermined relative pivotal movement and a proportion of the total relative movement may be effected by pivoting the workholders, the remainder being effected by pivoting the tools.

Preferably the design of the cams 49, 48 is such that the workholders are pivoted by the cam 49 to their practical limits and where extreme end spread is required or other special requirements make it necessary, the cam 48 will come into operation to pivot the tools to provide additional relative pivotal movement. During the pivotal movement of the workholders, a concentric part of the cam 48 will engage the follower 47 on the lever 46 so that no pivotal movement will be transmitted to the tools. Further, when the tools are being pivoted by the cam 48, a concentric part of the cam 49 will engage the follower on the lever 50 so that no pivotal movement will be transmitted to the workholders.

It will be understood that the cams 48, 49 may be designed so that the proportions of the total movement effected by pivoting the workholders and tools can be varied. Further, if desired, the workholders and tools may be pivoted simultaneously during a boring and drilling operation, the resultant combined pivotal movement giving the desired angular relation for effecting the end spread drilling and filling.

The movement of the workholders when effecting upright drilling and filling lengthwise of the brush stock and when effecting side spread filling is controlled by cams as described in U.S. Patent application Serial No. 324,120, now abandoned, the various cams being contoured to impart the necessary movements to the workholders and being operated in timed relation to the operation of the machine.

The operation of the machine is as follows:

At the start of a cycle of operations, the apparatus will be in the position indicated in FIGURE 1, and un-drilled brush stocks will be clamped to the workholders *a*, *a*¹, and pre-drilled brush stocks clamped to the workholders *b*, *b*¹, a "control" plate having a predetermined pattern being mounted on the holder *c*.

When the main drive of the machine is switched on, the tools D, F will be reciprocated in a vertical direction relatively to the workholders and actuated in known manner so that the brush stock on the workholder *a*¹ will be drilled by the tool D, and that on the workholder *b*¹ filled by the tool F, a series of predetermined pivotal movements being imparted to the tools during the drilling and filling operation to enable the desired angular relation between the workholders and tools to be effected for end spread during drilling and filling of the brush

stocks. At the completion of the drilling and filling operation, the main power is switched off and auxiliary power energised to supply fluid under pressure to the cylinders 28, 33, 40, so that the plunger 25 is withdrawn from locking engagement with the notch 27, the supply of fluid pressure to the cylinder 33 extends the piston rod 32 to move the bar 30 connected with the guide channels 29 of the workholders *b*, *b*¹ from the left to the right as viewed in FIGURE 1 of the drawing so that these workholders are moved transversely in a rectilinear path along the side bars 10 until the plunger 25 automatically engages the notch 27a. The workholder *b* will now be positioned under the filling tool F.

The supply of fluid under pressure to the cylinder 40 operates to retract the piston rod 39 to slide the boring tool D transversely from right to left as viewed

in FIGURE 1 of the drawing so that the tool is moved in a rectilinear path parallel to the plane of the brush stock supporting faces of the workholders *a*, *a*¹ to position the boring tool over the workholder *a*. During the transverse movement of the workholders *b*, *b*¹ and tool D, fluid under pressure is supplied to the cylinders 18 of workholders *a*¹, *b*¹ to unclamp the brush stocks mounted thereon.

The auxiliary power is switched off and the main power switched on to start the next drilling and filling operation, and the brush stock on the holder *a* is drilled and that on the holder *b* filled. During the drilling and filling operation, the filled brush stock on the holder *b*¹ is unloaded and the drilled brush stock from the holder *a*¹ substituted and an undrilled brush stock loaded on to the holder *a*¹.

At the end of the drilling and filling operation, the main power is switched off and the auxiliary power

energised to supply fluid under pressure to the cylinders 28, 33, 40, but this time the supply to the cylinders 33, 40 is in the reverse direction so that when the plunger 25 is released, the workholder assembly including the workholders *b*, *b*¹ will be moved by the retraction of the piston

32 back into the position indicated in FIGURE 1, and the boring tool D will be given a sliding movement in the reverse direction back into the position indicated in FIGURE 1. It will be understood that at the end of this movement, the plunger 25 automatically re-engages

in the notch 27. During the transverse movement, fluid under pressure is supplied to the cylinders 18 so that the brush stocks on holders *a*¹, *b*¹ are clamped and those on holders *a*, *b* unclamped.

The auxiliary power is switched off and the main power

switched on to start another drilling and filling operation, to drill the brush stock on holder *a*¹ and fill the brush stock on *b*¹, and during these operations the filled brush stock on the holder *b* will be removed and a drilled brush stock from the holder *a* substituted and an undrilled brush stock positioned on the holder *a*.

The cycle of operations is repeated so that, apart from the unloading and loading to the brush stocks, the apparatus operates automatically and continuously to drill and fill brush stocks.

It is to be understood that the pivotal mounting of the tools is not restricted for use with the particular machine illustrated in the accompanying drawings, but may be applied to any form of brush making apparatus wherein it is necessary to present brush holders in predetermined angular relation to boring and filling tools.

Further, the invention is not limited to apparatus having both boring and filling tools, but could be used with apparatus designed only to drill brush stocks or for filling predrilled brush stocks.

The axis (pivots 42) about which the tools pivot is located on an imaginary line substantially coinciding with the upper face of the brush stocks when mounted on the workholders when the latter are in the normal at rest position illustrated in the drawings. Further, it will be noted that this line lies in a vertical plane which

includes the axis of the drilling and filling tools. Accordingly, when the tools are pivoted, there will not be any linear displacement imparted to the drilling and filling tools relative to the brush stocks.

I claim:

1. Apparatus for operating on a brush stock comprising a workholder for supporting a brush stock, a tool for operating on one face of a brush stock supported on said workholder, means supporting said tool for pivotal movement relative to said workholder and means for imparting a series of predetermined pivotal movements to the tool so as to vary the angular relation between the tool and the brush stock on said workholder while a cycle of operations are carried out by said tool, the axis about which the tool pivots being located on an imaginary line substantially coincident with the said one face of the said brush stock when mounted on the workholder and when the latter is in the at rest position.

2. Apparatus as claimed in claim 1, wherein the said pivotal movements are imparted to a tool bar on which said tool is supported.

3. Apparatus for operating on a brush stock comprising a workholder for supporting a brush stock, means pivotally supporting said workholder, a tool for performing a cycle of operations on one face of a brush stock mounted on said workholder, means supporting said tool for pivotal movement, means for imparting a series of

predetermined pivotal movements to said tool relative to said workholder during part of said cycle and means for imparting a series of pivotal movements to the said workholder relative to said tool during another part of said cycle, the axis about which the said tool pivots being located on an imaginary line substantially coincident with the said one face of the brush stock when mounted on the workholder and when the latter is in the at rest position.

4. Apparatus as claimed in claim 1, wherein said tool comprises a drill for boring tuft receiving holes in the brush stock.

5. Apparatus as claimed in claim 1, wherein said tool comprises a filling tool for inserting tufts of bristles into predrilled holes in the brush stock.

6. In a brush making machine a workholder, means on said workholder for clamping a brush stock, a tool for operating on a brush stock clamped on said workholder, means for operating said tool to perform a cycle of operations on said brush stock, and means for effecting pivotal movement of said tool relative to the workholder to enable the angular relation between the workholder and tool to be adjusted during the performance of said cycle.
